UNITED STATES PATENT OFFICE

PERVIS S. ELMORE, OF DALLAS, TEXAS

DESIGN FOR A STRINGED MUSICAL INSTRUMENT OR SIMILAR ARTICLE

Application filed February 13, 1933. Serial No. 47,202. Term of patent 3½ years.

To all whom it may concern:

Be it known that I, PERVIS S. ELMORE, a citizen of the United States, residing at Dallas, in the county of Dallas and State of Texas, have invented a new, original, and ornamental Design for a Stringed Musical Instrument or Similar Article, of which the following is a specification, reference being had to the accompanying drawing, forming part thereof.

Figure 1 is a perspective view.

Figure 2 is a side elevational view, and

Figure 3 is a plan view of a stringed musical instrument or similar article, showing my new design.

I claim:

The ornamental design for a stringed musical instrument or similar article as shown.

PERVIS S. ELMORE.
